UNITED STATES PATENT OFFICE.

FRANK M. GRAY, OF MILWAUKEE, WISCONSIN.

WELL-REAMER.

SPECIFICATION forming part of Letters Patent No. 310,270, dated January 6, 1885.

Application filed August 16, 1884. (No model.)

To all whom it may concern:

Be it known that I, FRANK M. GRAY, a citizen of the United States, residing at Milwaukee, in the county of Milwaukee and State of Wisconsin, have invented certain new and useful Improvements in Well-Rreamers; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

In boring Artesian wells through certain loose formations it often becomes necessary to insert tubing to prevent the loose matter from closing in and filling the well.

The object of my invention is, first, to provide means for continuing the bore of the well of the same diameter below the tubing thus inserted as that above the tubing, and to do such work with a rigid tool of such dimensions as may be readily inserted and withdrawn through the tube; second, to change the capacity of a given drill, so that it will bore wells of various diameters greater than that of the well-tubing through which it is inserted; and, third, to provide means when prospecting for minerals for bringing to the surface samples of the various strata or ores through which the drill passes.

My invention is further explained by reference to the accompanying drawings, in which Figure 1 represents a vertical section of the drill as it appears in a well when in the act of enlarging the opening below the tubing, also the well, the well-tubing through which the drill has passed, and the surrounding strata. Figs. 2 and 3 are details. Fig. 4 is a detail, part in section, showing a device for adapting the same drill for wells of greater diameter.

Like parts are referred to by the same reference-letters throughout the several views.

A represents the shaft by which the drill is operated.

B is the drill, which consists of the screw-cut shank C, the eccentric-arm and point D, and the central guide, E.

F represents a section of tubing, such as is used to prevent the surrounding earth G falling in and closing the well. The diameter of the tube F, inside measure, is but slightly

larger than the greatest diameter of the drill-shank at B, sufficient space being allowed for inserting and withdrawing the drill.

55

It is obvious that in order to sink the tube farther it becomes necessary to continue the bore the same diameter below the tube that it is above, and of such dimensions that the tube will readily follow after the drill. To accomplish this object, I first bore a small hole, H, with an ordinary small drill, at the center of the well, in advance of the large drill, for the reception of the central guide, E. The central guide, E, may or may not be provided with a 60 drill, I, as desired. The small drill being withdrawn from the well, the large drill shown is inserted, when the guide E enters the hole H, as indicated. As the guide E enters the hole H the eccentric-arm D is thrown one side of 65 the center and beneath one side of the tube.

The drilling is accomplished by my device by raising and dropping the drill, and with each upward movement of the drill it is turned slightly, so as to bring the point of contact of the drill as it drops in a new place, whereby a cylindrical bore is formed. It is now obvious that as the drill rotates during the process of drilling the point D at its outer edge will describe a circle and drill an opening as much 70 greater in diameter than that of the interior of the pipe as the circle described by it is greater than the exterior of the pipe, whereby said opening will readily permit the pipe F to follow. The central guide, E, is secured to 75 the shank B by screw-and-socket joint T. If desired, however, the guide E may be permanently affixed to the shank, and the arm D may be detachably secured to it. When the point of the guide E is provided with a drill-point, I, it is attached to the guide by a screw-joint, K, as shown.

When using the drill in prospecting for minerals, I preferably use a tubular guide, E', as shown in Fig. 2, which is provided with an 80 aperture, L, located slightly below the point D of the drill, through which aperture specimens of the ore or other substances through which the drill passes falls into the tube, when, as the drill is elevated, they are brought to the 85 surface. When desirous to bore a well of greater diameter, I attach a tubular casing, M, eccentrically to the shank E by the eccentric collars N N, as shown in Fig. 4, the eccentric 90

100

tric side of the casing being arranged upon the opposite side of the guide E to that of the drill arm and point D, whereby as the drill rotates the point of the drill is caused to de-
5 scribe a still greater circle, and consequently to bore a hole of greater diameter proportionate to the eccentricity of the case.
As a means of protecting the guide E from wear when doing ordinary drilling, I substi-
10 tute the tubular casing O (shown in Fig. 3) for the eccentric casing or sheath M, which is retained in place by the collars P P. The lower collar, P, is secured to the guide by a screw-cut thread, *a*, and the upper collar may be keyed or otherwise securely affixed in any ordinary way. When the eccentric case M is used, the eccentric collars N N are held in place by said collars P P. (Shown both in Figs. 3 and 4.)

20 Having thus described my invention, what I claim as new, and desire to secure by Letters Patent, is—

1. In a reciprocating drop-drill, the combination, with the drill-shaft A, of the shank B, having a blunt eccentric-arm provided at its lower end with a cutting-point, D, by which the hole is enlarged below the tubing, and a central guide-shaft, E, serving, as it operates in the lead-opening, to hold said cutting-point

at a uniform distance from the central hole, 30 whereby said point will drill a hole of greater diameter than the tubing, substantially as set forth.

2. The combination of shaft A, shank B, having eccentric-arm and cutting-point D, with the 35 detachable tubular shank E', provided with apertures L, substantially as and for the purpose specified.

3. The combination of the shaft A, shank B, having eccentric-arm and point D, central guide-shaft, E, tubular casing O, and retaining-collars P P, as set forth. 40

4. The combination of shaft A, shank B, having eccentric-arm and point D, central guide-shaft, E, eccentrically-arranged casing M, eccentric collars N N, and retaining-collars P P, as set forth. 45

5. The combination of the shaft A, shank B, having blunt eccentric-arm provided at its lower end with a cutting-point, central guide, 50 E, and drill-point I, attached to the lower end of said central guide E, substantially as set forth.

In testimony whereof I affix my signature in presence of two witnesses.
